ADJUSTMENT MEANS FOR RIVET FEEDING
HOPPERSThomas J. Doyle, South Braintree, Mass., assign-
or to Tubular Rivet and Stud Company, Quincy,
Mass., a corporation of Massachusetts

Application July 13, 1948, Serial No. 38,431

3 Claims. (Cl. 218—2.1)

1

This invention relates to an adjustment means for rivet feeding hopper device and more particularly to a rivet feeding device for a rivet setting machine.

The invention has for an object to provide a novel and improved rivet setting machine having a rivet feeding device characterized by novel structure for effecting adjustment of the cooperating elements whereby to enable the feeding device to operate with maximum efficiency.

The invention has for a further object to provide a novel and improved rivet setting machine having a rivet feeding device of the cone hopper type characterized by novel structure for effecting adjustment of the cone hopper in a simple manner whereby to enable the feeding device to operate with maximum efficiency.

With these general objects in view, and such others as may hereinafter appear, the invention consists in the rivet setting machine and in the various structures, arrangements and combinations of parts hereinafter described and particularly defined in the claims at the end of this specification.

In the drawings illustrating the preferred embodiment of the invention, Fig. 1 is a front elevation of a rivet setting machine embodying the present invention, the rivet feeding device being shown in cross section as viewed from the line 1—1 in Fig. 2; Fig. 2 is a side elevation of the present rivet setting machine; Fig. 3 is a cross sectional view taken on the line 3—3 of Fig. 2; Fig. 4 is a cross sectional view taken on the line 4—4 of Fig. 2; Fig. 5 is a cross sectional view taken on the line 5—5 of Fig. 1; and Fig. 6 is an enlarged plan view in cross section, as viewed from the line 6—6 of Fig. 1, showing the adjusting mechanism to be referred to.

In general, the present invention contemplates a novel rivet setting machine having a cone type rivet feeding hopper characterized by provision for effecting adjustment of the operating parts in a novel and simple manner whereby to maintain predetermined clearances for the heads of the rivets in the feeding device for most efficient operation. The illustrated cone type rivet feeding hopper comprises, in general, an intermittently rotated conical hopper arranged on a horizontal axis and having a plurality of radial slots formed in the periphery of its open end through which the leg or shank portion of a rivet may enter with the head portion straddling the edges of the slot, and, a cooperating stationary end or cover portion spaced a predetermined distance from the open end of the cone to provide clear-

2

ance for the height or thickness of the rivet heads. The inner edges of the radial slots are flared outwardly in a manner such as to guide the rivets thus suspended into a horizontal position with the heads disposed between the ends of the cone and the stationary member, the rivets being subsequently released into a track or guideway arranged to deliver successive rivets into operative position to the rivet setting elements.

10 In practice, the cone portion of the hopper is mounted to be movable, longitudinally relative to the stationary end member to permit retraction of the hopper when it is desired to empty the same or to clear the cone in the event of a jam, and, in the illustrated embodiment of the invention, a latch member is provided for aligning and maintaining the hopper in a predetermined fixed position to assure replacement of the cone in a position to maintain the predetermined spacing between the end of the cone and the stationary end member.

15 The spacing between the end of the cone and the stationary end member is preferably made to accommodate the specific size of rivet to be fed, and, prior to the present invention, a different latch member was used for each different size of rivet so that a fixed spacing could be maintained. However, due to inaccuracies in manufacture, or to accumulation of maximum tolerances in one direction in the various parts of the assembled cone, the clearance spacing for the rivet heads might vary considerably from the predetermined spacing required so that, in operation, a jam of the rivet heads between the end of the cone and the stationary cover member might occur, the feeding of relatively small rivets being particularly troublesome in this respect, especially if the spacing was slightly greater than that required for efficient operation.

20 Prior to the present invention no provision was made for effecting adjustment to obtain the critical spacing required, reliance being placed entirely on the accuracy of the finished parts in their assembled relation to provide the predetermined clearance for the heads, and if the assembled structure did not operate efficiently, it had to be disassembled to correct the inaccuracies in manufacture and to replace some of the parts with others of a corrective size, the entire assembly operation being more or less of a cut and try procedure, all of which consumed considerable time and expense in assembly and added substantially to the cost of manufacture of the feeding unit. Furthermore, when a rivet having a different head thickness was to be used some of the

parts had to be replaced to accommodate the different size rivet and in commercial use of the machines this might necessitate sending a machine back to the factory for proper fitting of the parts with the accompanying loss of production.

In accordance with the present invention, provision is made for adjusting the latch member above referred to in a simple and convenient manner arranged to effect bodily movement of the cone assembly on its axis to obtain the required spacing relative to the stationary end member for most efficient operation. Provision is also made for locking the latch member in its adjusted positions so that when the cone assembly is retracted away from the stationary end member and subsequently advanced into operative rivet feeding position, the latch member will be effective to maintain the cone in its adjusted position. The present adjusting mechanism may also be used with advantage in adjusting the head clearance between the cone and the stationary end member to accommodate a different size of rivet, the adjustment being easily and quickly made by the operator or attendant without servicing by the manufacturer.

Referring now to the drawings, the present invention is illustrated as embodied in a rivet setting machine of the type having a reciprocal driver 10 arranged to cooperate with an anvil 12 to perform the riveting operation in the work, and during the riveting operation the work may be manually supported on the anvil by the operator. The driver 10, as herein shown, is slidingly supported in a bearing member 15 forming part of a bracket 14 and is arranged to be reciprocated by any usual or preferred driving mechanism such as a one revolution crank, not shown, and through connections including a link 16 connected to one arm 18 of a two-armed lever pivotally mounted at 20 in the bracket 14. The other arm 22 of the lever is connected by slotted links 24 to the upper end of the driver 10, as shown in Fig. 2.

The rivet to be set is supported in alignment with the driver by a yieldably mounted separable holder 26 comprising two opposed half sections shaped to form a socket in which the rivet is disposed in an upright position with the head uppermost as shown in Fig. 1. The half sections are supported by opposed flexible straps 28 depending from a hub member 30 slidingly fitted about the body of the driver 10 and movable therewith during the descent of the driver when the latter engages the head of the rivet supported therein. The rivet holder 26 is normally held in its elevated position, as shown, by a spring 32 connected between the hub member 30 and a driver link 24 and, is limited in its upward movement by engagement of the upper end of the sliding hub 30 with the lower end of the bearing member 15. In operation, the holder 26 is arranged to move with the driver for a part of the downward stroke until the end of the rivet engages the anvil, the holder being limited in its descent by an adjustable stop screw 36 carried by an extension 38 attached to the hub member 30, and the stop screw being arranged to engage a stud 40 fast in the bearing member 15 and extended through a slotted portion 42 of the extension 38. In its elevated position, the holder 26 is supported in alignment with a feed chute or guideway 44 from which the rivets are successively released, each cycle of operation to be guided into the holder.

In the operation of the riveting machine, when

the driver descends it engages the head of the rivet in the holder 26 causing descent of the holder along with the driver 10 until the movement of the holder is interrupted by the stop screw 36, whereupon the rivet is forced through the holder and into the work to be riveted during the continued descent of the driver to perform the rivet setting operation. The half sections of the holder are caused to spread apart when the rivet is forced through the holder by virtue of the flexible straps 28, and, during the continued descent of the driver, the holder remains in frictional engagement with the body of the driver. Upon elevation of the driver, the holder 26 is returned to its elevated position in alignment with the guideway 44 to receive a succeeding rivet released therefrom. As herein shown, the guideway 44 forms a reservoir for the rivets supplied thereto by the hopper feeding device, indicated generally at 46, and the rivets in the guideway are released successively by an escapement mechanism, indicated generally at 48, arranged to be operated by connections including a lever having one arm 50 engageable with the escapement and a second arm 52 having a cam surface engageable with a stud 54 carried by the rivet setting arm 22, one rivet being released each time the holder is returned into alignment with the guideway at the end of a rivet setting operation.

The upper end of the guideway is supported in operative engagement with the feeding device 46 and the lower end is supported by a depending bracket 56 attached to the machine frame. As illustrated in Figs. 1 and 2, the rivet feeding device includes a stationary end member 58 supported from the bracket 14 by an intermediate bracket 58, and a rotatable cone hopper 60 having a plurality of radial slots 62 at its larger or open end. The cone hopper 60 is supported for rotation with a horizontal shaft 64 journaled in the hub 66 of the stationary end member. In the operation of the device, the rivets are supplied to the unit through an opening 68 provided in the stationary member, and as the cone rotates the shank or leg portions of the rivets are received in the radial slots with the head portions straddling the edges of the slots and are guided into a horizontal position by the outwardly flared curvature of the inner surface of the cone adjacent the open end thereof. The rivets are thus supported in a horizontal position with the head portions interposed between the end of the cone and the inner surface 70 of the end member. The shaft 64 is arranged to be intermittently rotated in a counterclockwise direction, viewing Fig. 2, by a ratchet 65 fast on the shaft 64 and a co-operating pawl 67 carried by one arm 69 of a bell crank loosely mounted on one end of the shaft 64. The bell crank is arranged to be rocked each cycle of operation by a link 71 connected between the driver operating arm 18 and the second arm 13 of the bell crank.

Referring now to Fig. 2 the rivets thus supported are maintained within the radial slots by engagement of the rivets with the rim portion 72 of the end member. The rivets are permitted to fall out of the radial slots when the cone is rotated in a counterclockwise direction to present the slots beyond the guideway inlet 75 by virtue of a grooved portion 74 in the end member 58 which provides clearance for the head of the rivet, as shown in Fig. 3. The rivet is maintained in a horizontal position beyond the influence of the cone 60 and with the shank of the rivet in rolling contact with the rim portion 76 of the

stationary member and being disposed in a space 79 between the rim and the cone. A rivet thus released from the radial slot may roll by gravity into the guideway inlet 75, one side of the inlet being defined by an extended portion 77 of the element 72 cooperating with the outside diameter of the cone and forming a baffle to deflect the rivets into the guideway, as clearly shown in Figs. 2 and 4. It will be understood that in practice the guideway 44 may be completely filled with rivets and that the rivets may be disposed along the arcuate space 79 forming in effect a continuation of the guideway and being defined by the outside of the cone and the rim portion of the stationary end member, the rivets being progressively advanced as they are successively released by the escapement mechanism 48. Surplus rivets carried by the cone and prevented from entering the arcuate space 79 by previously positioned rivets may drop back into the bulk supply when the cone is rotated to dispose the radial slots in a vertical position.

Referring now to Fig. 1, the cone portion 60 is provided with an end wall 63 at its smaller end which is secured to a flanged sleeve 76 slidably mounted on the shaft, the sleeve being connected to the shaft 64 by a key 78 cooperating with an elongated keyway 80 arranged to permit longitudinal movement of the sleeve on the shaft. The cone is yieldingly and frictionally supported on the sleeve by a spring washer 84 bearing against one side of the end wall, the other side being provided with a fiber friction washer 86 interposed between the end wall and the flanged portion 85 of the sleeve, so that in operation, in the event of a jam, the cone may come to rest to prevent damage to the operating parts. As herein shown, the spring washer 84 is maintained in yielding engagement with the end wall 63 by an adjusting nut 88 engageable with a threaded portion of the sleeve, a spacing collar 90 and fiber friction washer 92 being interposed between the nut 88 and the spring washer 84, as clearly shown in Fig. 6. The outer end of the sleeve is provided with a nut 94 threadedly engaged with the sleeve and forming a handle by which the cone assembly may be bodily moved longitudinally of the shaft.

In order to maintain the cone assembly in its predetermined spaced relation relative to the inner wall 70 of the stationary member, and to permit retraction of the cone to empty the hopper or to clear the same in the event of a jam, a quick release latch mechanism is provided as indicated generally at 95, and which as herein shown, includes an elongated pivoted latch member or bar 96 having a transverse grooved portion 98 arranged to cooperate with the inner edge of a ring member 100 carried by the nut 94 and interposed between the outer end of the sleeve 76 and a flange portion 102 of the nut 94. The ring member 100 is threadedly engaged with the nut 94 and slidably mounted on the shaft 64, the ring member being coextensive with the outer or threaded end of the sleeve in its assembled relation, as shown in Figs. 1 and 6.

The latch member 96 is generally rectangular in cross section and is arranged to fit in a longitudinally grooved portion 104 formed in the shaft 64, the upper face of the latch member being curved upon a curvature substantially equal to that of the shaft so that in its depressed position, the latch member conforms to the surface of the shaft, as shown in Fig. 5, to permit

retraction of the cone assembly thereover. The latch member 96 is pivotally mounted on a stud 106 carried by a collar 108 secured to the outer end of the shaft by a through pin 110 and is normally urged upward into operative engagement with the inner edge of the ring 100 by a spring 112 supported in a socket formed in the shaft and engageable with the underside of the latch member. The outer end of the sleeve 76 may be provided with a longitudinal slot 101 to provide clearance for the end of the latch member in its engaged position, as shown in Fig. 1.

From the description thus far it will be seen that upon manual depression of the latch member 96 to free the latch from the ring 100 the cone assembly may be bodily moved longitudinally on the shaft 64 away from the stationary end member 56 as indicated by the dotted lines in Fig. 1, and that upon movement in the opposite direction the latch will be urged into operative engagement with the ring to position the cone assembly in its predetermined spaced relation with respect to the inner wall 70 of the stationary end member 56.

Prior to the present invention the predetermined spacing between the end of the cone 60 and the stationary member was determined by the length of the latch bar 96, a different latch bar being provided for each unit when a different spacing was required. In practice, it will be seen that this spacing might vary considerably due to inaccuracies in the manufacture of the various parts making up the cone assembly, and, in some instances, particularly when relatively small rivets are being fed, the variation in the spacing or head clearance caused considerable difficulty because of the liability of jamming of the rivets between the cone and the stationary member.

In the illustrated embodiment of the invention the latch bar 96 is pivotally mounted on an eccentric portion 114 of the stud 106, the head of the stud having a slotted portion for convenience in rotating the stud and the threaded end of the stud being provided with a nut 116 for locking the stud in its adjusted position. With this construction it will be seen that rotation of the eccentric stud 106 will change the pivotal point of the latch bar 96 and effect bodily movement of the cone assembly on the shaft 64 to obtain the desired spacing required between the open end of the cone and the stationary wall 70 and that the stud may be locked in its adjusted position by the locking nut 116. The mechanism for thus effecting the described desired adjustments is simple and positive in operation and eliminates all of the described difficulties heretofore experienced with the prior machines.

While the preferred embodiment of the invention has been herein illustrated and described it will be understood that the invention may be embodied in other forms within the scope of the following claims. Having thus described the invention what is claimed is:

1. In a rivet setting machine, a rivet feeding device comprising a horizontally mounted and intermittently rotated shaft, a cone shaped hopper mounted for rotation with said shaft and having a plurality of radial slots at its open end arranged to guide the rivets into a position with the head portions directed outwardly, a stationary end wall cooperating with the open end of said cone and spaced a predetermined distance therefrom to provide a clearance space for said rivet heads, said cone being capable of

movement longitudinally of said shaft to permit access to the interior of the cone, a pivotally mounted releasable latch member carried by said shaft and cooperating with said cone adapted to maintain the same in its predetermined spaced relation with respect to said stationary end wall during the rivet feeding operation, means for adjustably moving said latch member longitudinally of the shaft to vary said predetermined spacing for most efficient operation, and means for locking the latch member in its adjusted position.

2. In a rivet setting machine, a rivet feeding device comprising a horizontally mounted and intermittently rotated shaft, a cone shaped hopper mounted for rotation with said shaft and having a plurality of radial slots at its open end arranged to guide the rivets into a position with the head portions directed outwardly, a stationary end wall cooperating with the open end of said cone and spaced a predetermined distance therefrom to provide a clearance space for said rivet heads, said cone being capable of movement longitudinally of said shaft to permit access to the interior of the cone, an annular member carried by said cone, a manually depressable latch member carried by said shaft and normally urged into cooperating engagement with said annular member adapted to maintain the cone in its predetermined spaced relation with respect to said stationary member during the rivet feeding operation, a pivotal mounting for said latch member, means for adjusting said pivotal mounting to vary said predetermined spacing for most efficient operation, and means for locking said pivotal mounting in its adjusted position.

3. In a rivet setting machine, a rivet feeding

5
10

device comprising a horizontally mounted and intermittently rotated shaft, a cone shaped hopper mounted for rotation with said shaft and having a plurality of radial slots at its open end arranged to guide the rivets into a position with the head portions directed outwardly, a stationary end wall cooperating with the open end of said cone and spaced a predetermined distance therefrom to provide a clearance space for said rivet heads, said cone being capable of movement longitudinally of said shaft to permit access to the interior of the cone, an annular member carried by said cone, a manually depressable latch member carried by said shaft and normally urged into cooperating engagement with said annular member adapted to maintain the cone in its predetermined spaced relation with respect to said stationary member during the rivet feeding operation, a pivotal mounting for said latch member including a collar secured to said shaft, and means for adjusting said pivotal mounting to vary said predetermined spacing for most efficient operation, said pivotal mounting including an eccentric stud carried by said collar and adapted to be rotated to change the pivotal point of said latch member, and a nut cooperating with said stud for positively locking the stud in its adjusted position.
